UNITED STATES PATENT OFFICE.

LOUIS W. DOWNES, OF PROVIDENCE, RHODE ISLAND.

APPARATUS FOR APPLYING INSULATION TO ELECTRICAL CONDUCTORS.

No. 861,021.

Specification of Letters Patent.

Patented July 23, 1907.

Application filed July 7, 1904. Serial No. 215,694.

To all whom it may concern:

Be it known that I, LOUIS W. DOWNES, of Providence, Rhode Island, have invented a new and useful Improvement in Apparatus for Applying Insulation to Electrical Conductors, which invention is fully set forth in the following specification.

The present invention consists of an improved apparatus for applying fibrous insulating material—particularly asbestos—to the surface of an electric conductor or wire, by spirally wrapping said material about the wire. The apparatus is especially designed for the production of what is known as "magnet-wire".

As is well known, asbestos fibers are short and relatively weak; when worked up into sliver or analogous form, there is little coherence between the fibers and they pull apart or break under slight strain; asbestos wool in the form of sheets, strands with substantially no twist, or sliver (better known to the trade as "roving,") is therefore extremely delicate and possesses hardly enough tenacity to support its own weight, even in short lengths. For these reasons it has been customary to apply asbestos to conductors in the form of yarn, which is asbestos sliver twisted to give it greater tenacity. While the formation of the asbestos into yarn enables it to be more readily handled, there is little, if any, advantage after it is applied to the conductor. There are some disadvantages; the natural lumpiness of asbestos is more apparent in the yarn than in sliver, for example. Consequently, a wrapping of asbestos yarn presents greater unevenness or less uniformity in thickness than a wrapping of asbestos in the form of untwisted strands, sheets or sliver; furthermore, when applied in the sliver or analogous form, the fibers adhere to the wire in a loose, fluffy or flocculent condition, enabling them to be readily compacted into an even layer, and to be formed into an insulating covering a minimum thickness, such as required in the case of "magnet-wire." The subsequent finishing operations can therefore be more readily and effectively carried out when the fibers are applied in sliver or analogous form.

The principal object in view is to provide an apparatus capable of applying asbestos in the form of substantially untwisted strands, bands or sheets, to an electrical conductor, with the advantages, principally, that the asbestos in this form is cheaper, and that the subsequent finishing operations can be more effectively and satisfactorily performed. I am aware that it has heretofore been proposed to wrap asbestos sliver about a wire by causing the wire instead of the asbestos to rotate; but this method is seriously objectionable, if not impracticable. In covering heavy conductors, for example, it involves rotation of heavy masses of metal which is both a difficult and dangerous operation. And while means have heretofore been provided

for wrapping asbestos yarn on a wire by revolving the yarn about the wire, no means have, I believe, been heretofore devised capable of applying delicate, substantially untwisted asbestos strands, sheets or sliver to a wire in a similar manner.

In apparatus embodying my present invention, the means for feeding the asbestos to the wire rotate about the latter, and the asbestos is conveyed in a loose and flocculent band, narrow sheet or layer to the point of its application to the wire, being thereby relieved of all strain tending to break the same.

In the preferred form of apparatus herein shown, the asbestos is formed into an untwisted strand while in transit from a hopper to the point of its application to the wire.

These and other features of the apparatus will be more fully described by reference to the accompanying drawings, in which

Figure 1 is an elevation of a machine embodying my invention; Fig. 2 is an elevation of part of the machine at right angles to Fig. 1; Fig. 3 is a vertical sectional view through the rotary carrier or table and parts thereon, on line 3—3 of Fig. 5; Figs. 4 and 5 are transverse sectional views, on a reduced scale, the former on line 4—4, and the latter on line 5—5, Fig. 3.

Referring first to Figs. 1 and 2, pulley 6, driven from a suitable source of power, carries a bevel gear 7, meshing with a similar gear 8 on a vertical shaft 9. A handle 10 at the upper end of the shaft serves to turn the parts of the machine to any desired position when the power driving means are disconnected. A worm 11 on shaft 9 drives a worm-wheel 12 (Fig. 2) on a shaft 13; gear wheel 14 on the other end of said shaft slowly rotates a large gear wheel 18 fixed on shaft 19 through gear wheel 15, shaft 16 and gear wheel 17.

The electric conductor or wire 20 passes upwards through a reservoir 21, containing a liquid or semi-liquid adhesive material (preferably shellac), through the rotary carrier 22 where the insulation is applied, through a guide 24, and then several times around a rotating drum 23 fixed on shaft 19. Rotation of drum 23 slowly draws the wire through the machine; from said drum the covered wire may pass to suitable finishing apparatus, such, for example, as shown in my Patent No. 534,785 of February 26, 1895. Carrier 22 is rotated by gears 25, 26 and 27, the first on shaft 9.

Referring now more particularly to Figs. 3, 4 and 5, it will be seen that the mechanism for applying the asbestos to the wire is mounted in or upon and rotates with the carrier. 28 is a hollow stud or axle fixed to a part 29 of the main frame by a nut 30. The carrier comprises a plate or table 31, which turns loosely upon the upper extremity of axle 28, also a cup-like casting 32 having a central sleeve 33 which fits loosely about and turns on axle 28. Gear 27 fixed to sleeve 33 imparts rotary motion to the carrier about the axle 28.

Six short vertical shafts 34 to 39 are journaled in and project above and below table 31. Wheels 41, 42, 43, 44, 45 are removably fixed on the upper ends of shafts 35, 36, 37, 38 and 39 respectively, by nuts 46. The surfaces of these wheels are covered with card cloth, making them in effect carding wheels. Two pulleys 47, 48, fixed on the upper ends of shaft 34 and a stud 40 respectively, by nuts 49, are connected by a belt or endless conveyer 50 having projecting teeth similar to card clothing. These carding wheels and the belt are in operation rotated in the direction indicated by the arrows in Fig. 5 by means of the following gearing located beneath table 31; gear wheels 51, 52 on shafts 38 and 39 mesh with each other; gear 52 in turn meshes with a fixed gear 53 preferably cast integral with axle 28. Shaft 39 also carries a sprocket wheel 54. A sprocket chain 55 passes over said wheel 54 and around other sprocket wheels 56, 57, 58 and 59 on shafts 37, 36, 35 and 34, respectively. Preferably the diameter of sprocket 54 is slightly less than that of 56, of 56 slightly less than that of 57, and of 57 slightly less than 58, producing corresponding differences in the speed of movement of the parts carried by the shafts of these sprockets.

60 is a chamber or hopper for asbestos located above table 31 within an annular shell 61 which incloses all of the mechanism above the table; a removable cover 62 for the shell also closes the hopper 60. The wire passes through an opening 63 in the cover.

64 is a feed-plate movable on two guide rods 64 is impelled forward by springs 65, tending to force the asbestos through the discharge opening at the contracted end of the hopper. Any other suitable means for feeding the asbestos to the rolls may, of course, be employed.

66 is a curved shield extending partly around the wire and preventing asbestos, except that delivered from belt 50, from attaching itself to the sticky wire.

In the operation of the apparatus the wire 20 slowly drawn upward through the receptacle 21 and carrier 22 receives in the former a coating of adhesive material. The hopper 60 is preferably filled with asbestos fiber previously carded to bring it to such condition as to be worked to the best advantage; good results may, however, be obtained by filling the hopper with asbestos fiber in its raw, woolly, uncarded state. The asbestos fiber caused to protrude from the delivery end of the hopper between the carding and feeding rolls or wheels 44 and 45 is drawn from the hopper by the action of said rolls. The inclination of the carding teeth on roll 45 causes the asbestos to adhere thereto rather than to roll 44. Roll 43, also having inclined teeth, and rotating with greater surface speed than roll 45, picks up and disengages the asbestos from the latter and carries it forward until it is in turn picked up by the inclined teeth of roll 42, the surface speed of which is greater than that of roll 43. Roll 41 disengages the asbestos from roll 42 and delivers it onto conveyer belt or apron 50, the surface speed of which is preferably faster than that of roll 41, which in turn delivers it into contact with the sticky surface of the wire to which it adheres and is thereby licked up and separated from the conveyer apron. The action of the carding rolls and apron is to straighten out and assemble the

fibers into a band or narrow sheet of substantially untwisted parallelized fibers, similar to but wider than ordinary asbestos sliver and to apply them to the conductor in this condition. As the carrier rotates about the wire while the latter moves longitudinally, 70 the asbestos band is spirally coiled or spread upon the wire in an evenly distributed layer of uniform thickness; but to this end the relative speeds of movement of the several parts must, of course, be properly timed. As the sliver-like band is supported practically up to the point of its application to the wire, no tensile strain being placed upon it, there is practically no danger of breaking the band with consequent imperfections in the covering. The movement of the apron or belt 50 on its pulleys 47 and 48, simultaneous 80 with the rotation of the carrier around the non-rotating wire, is of importance in effecting a practically continuous spiral winding or wrapping of the fibers upon the longitudinally moving wire. The linear movement of the card belt continuously advances fiber bearing portions thereof to the wire as the belt is carried around the wire by rotation of the carrier. The wire or conductor leaves the carrier bearing a spirally wound adherent covering of asbestos fibers in a somewhat flocculent or fluffy though materially straightened state. In this condition the covering may, by subsequent operations, be more readily compacted, matted or compressed into a thin coherent fabric of uniform thickness, than if the asbestos be applied, for example, in the form of yarn. From the apparatus herein described, the conductor may pass to any suitable apparatus for compressing and compacting the covering, for example, that described in my patent above mentioned. The covering may also be impregnated or coated with any suitable fire-proofing and water-proofing composition. One, two or more layers of asbestos may be applied, according to the thickness of insulation desired.

The invention is not restricted to the particular form of apparatus herein illustrated and described, 105 as modifications may be made without departing therefrom.

My applications Sr. No. 215,695, filed July 7, 1904, and Sr. No. 265,389, filed June 15, 1905, illustrate other forms in which the generic invention herein 110 disclosed may be embodied.

What I claim is:

1. In apparatus for applying fibrous insulating material to a conductor, a carrier and means for rotating the same about the conductor, a hopper or chamber on the carrier for the fibrous material, carding means on the carrier for conveying fibrous material from the hopper and for delivering the same into contact with the surface of the conductor in the form of a band or strand, and driving connections for actuating said carding means while the carrier rotates.

2. In apparatus for applying fibrous insulating material to a conductor, a carrier and means for rotating the same about the conductor, a hopper or chamber on the carrier for the fibrous material, carding means on the carrier for conveying fibrous material from the hopper and for delivering the same into contact with the surface of the conductor, said means comprising a traveling feed surface supporting the fibrous material and moving in close proximity to the conductor at the point the fibrous material is applied thereto, and driving connections actuating said carding means while the carrier rotates.

3. In apparatus for applying fibrous insulating material to a conductor, a carrier and means for rotating the same

about the conductor, a hopper or chamber on the carrier for the fibrous material, carding means on the carrier for conveying fibrous material from the hopper and for delivering the same into contact with the surface of the conductor, said means comprising carding wheels or rolls and a conveyer belt receiving the fibrous material from the rolls and moving in close proximity to the conductor at the point the fibrous material is applied thereto, and driving connections actuating said carding means while the carrier rotates.

4. In apparatus for applying fibrous insulating material to a conductor, the combination of a carrier comprising a supporting plate or table and having an axial opening through which the conductor passes, means for rotating the carrier on its axis, a hopper or chamber on one side of said table for the fibrous material, carding means mounted on the same side of the table for conveying fibrous material from the hopper and for delivering the same into contact with the surface of the conductor in the form of a band or strand, and driving connections mounted on the other side of the table for actuating the carding means while the carrier rotates.

5. In apparatus for applying fibrous insulating material to a conductor, the combination of a carrier comprising a supporting plate or table and having an axial opening through which the conductor passes, means for rotating the carrier on its axis, a hopper or chamber, carding means comprising carding rolls and a conveyer-belt moving in close proximity to the conductor, said hopper, rolls and belt being all mounted on the same side of the table, shafts passing through the table to the carding rolls and con-

veyer-belt, and gearing connected to said shaft on the other side of the table to actuate the carding means while the carrier rotates.

6. In apparatus for applying fibrous insulating material to a conductor or wire, a carrier and means for rotating the same about the conductor and for simultaneously imparting relative movement to the conductor and carrier in a direction longitudinal to the conductor; a carding surface mounted on the carrier and adapted to deliver fiber to the wire, and driving connections for advancing the carding surface on its bearings on the carrier during rotation of the latter to present fiber-bearing portions of said surface to the surface of the wire.

7. In apparatus for applying fibrous insulating material to a conductor or wire, a carrier and means for rotating the same about the conductor and for simultaneously imparting relative movement to the conductor and carrier in a direction longitudinal to the conductor, a carding surface mounted on the carrier and adapted to deliver fiber to the wire, means for delivering fiber to the carding surface, and driving connections for advancing the carding surface on its bearings on the carrier during rotation of the latter to continuously present fiber-bearing portions of said surface to the surface of the wire.

In testimony whereof I have signed this specification in the presence of two subscribing witnesses.
